UNITED STATES PATENT OFFICE.

MAURITZ OLSON, OF BRIDGEPORT, CONNECTICUT, ASSIGNOR TO THE A. H. NILSON MACHINE CO., OF BRIDGEPORT, CONNECTICUT, A CORPORATION OF CONNECTICUT.

WIRE-CHAIN LINK.

Application filed May 31, 1922. Serial No. 564,709.

To all whom it may concern:

Be it known that MAURITZ OLSON, a citizen of the United States, and resident of Bridgeport, in the county of Fairfield and 5 State of Connecticut, has invented certain new and useful Improvements in Wire-Chain Links, of which the following is a specification.

This invention relates to wire chain, the 10 links of which are alike in construction and each made of a single piece of wire bent to form a loop and a transversely arranged eye through which the loop of the adjoining link is joined during the automatic manu- 15 facturing and assembling of the chain.

The object of my invention is to improve upon that style of wire chain known as "Triumph chain," which is similar in some respects to the construction of chain link 20 shown in Patent #564,406 and particularly to produce a link the side members of the loop of which are substantially parallel with each other and the shoulders of which formed at the intersection of the eye and 25 loop are arranged at an intersecting angle. A further and essential feature of the invention is to provide a link, the end portions of the wire of which are bent in around the shoulders of and in alignment with the 30 wire of the eyes and against the peripheral or back portion of the eye in a way to cover the two wire ends, and to form a finished and smooth running link.

The invention further resides and consists 35 in the construction and novel form of link hereinafter to be more fully described, illustrated in the accompanying drawing and pointed out in the claims hereto appended.

Similar characters of reference denote like 40 or corresponding parts through the several figures of the accompanying drawings forming part of this specification and upon which:-

Fig. 1 shows a top plan view of a piece of 45 wire chain, the several links of which are constructed in accordance with the features of my invention;

Fig. 2 is an edge view of the chain shown in Fig. 1; and

50 Fig. 3 shows a bottom plan view of the chain seen in Fig. 1.

All of the links shown in the drawing are alike in construction and each is formed from a single piece of wire of proper length, 55 bent at its center to form a loop, the end

portions being shouldered and brought together and curled to form a closed eye through which the end portion of the loop of the adjoining link is hingedly connected.

In the drawing, A represents the loop portion of the link and B the eye portion. The loop comprises an outer rounded end portion *a*, two parallel side members *b*—*b*, a pair of inwardly disposed shoulders *c*—*c* formed at the intersection of the loop and eye, sometimes designated as the shank. These shoulder portions are formed by inwardly deflected portions of the side members, arranged in the same plane as that of the two side members *b*—*b* though at intersecting angles. The eye is of double construction and comprises two similarly formed end portions of the wire, positioned side by side and so shaped and tied that their openings align one with the other, better to accommodate the loop portion of the adjoining link.

The side members are bent in at intersecting angles to form the shoulders *c*—*c* and are then bent around at an acute angle 80 to form the two eye portions *d*—*d*. The eyes are substantially round in shape and are secured by the ends being tied to the shoulders. The end portions *e*—*e* of the wire are passed over the outer side of the two shoulders and bent in toward each other and then disposed forward lengthwise of the link and along side of each other with their ends *f*—*f* positioned against the periphery of the link in a way to cover the said 85 ends and to form a link with no rough projecting wire ends, thereby forming a chain that is smooth to handle and which will run through the hand without injuring the same.

From the foregoing it will be seen that the two end portions *e*—*e* are disposed toward and in alignment with the plane of the bends of the wire forming the two eye members and that the two ends proper are positioned against the outside of the wires forming said eyes.

Having thus described my invention, what I claim and desire to secure by Letters Patent is,

1. A wire chain link made from a single piece of wire and bent to form, and comprising a loop portion and a double eye portion, shoulders formed at the intersection of loop and eye and at intersecting angles 110

with respect to each other, the double eye of the link comprising two like eyes positioned against each other and bent around to align with each other the end portions of the wire being turned inward through the loop and positioned side by side against each other, the ends proper being disposed against the periphery of the respective eyes in a way to cover said ends and form a smooth running link.

2. A wire chain link made from a single piece of wire and bent to form, and comprising a loop portion and a double eye portion, the said loop portion including a rounded outer end and parallel side members, and shoulders formed intermediate the opposite side members and at intersecting angles with respect to each other, the double eye of the link being adjacent to the shoul-

ders and comprising two like portions of the wire positioned against each other and bent around together to form aligned eyes, said end portions of the wire being positioned against the outside of the respective shoulders of the loop and bent around said shoulders and through said loop and further positioned side by side against each other and in parallel planes and having their ends proper disposed against the outer peripheries of the eye in a way to cover said ends and form a smooth running link.

Signed at Bridgeport in the county of Fairfield and State of Connecticut this 25 day of May A. D., 1922.

MAURITZ OLSON.
